CLAIM

We claim, the ornamental design for a portable information terminal, as shown and described.

DESCRIPTION

FIG. 1 is a front view of a portable information terminal showing our new design;

FIG. 2 is a rear view thereof;

FIG. 3 is a right side view thereof;

FIG. 4 is a left side view thereof;

FIG. 5 is a top plan view thereof;

FIG. 6 is a bottom plan view thereof;

FIG. 7 is a front perspective view thereof; and,

FIG. 8 is a back perspective view thereof.

The portable information terminal can function as a computer, a media reproducing device (e.g., a music player, a movie player, or a game player), a media storage device, a communication device (e.g., a portable telephone), or the like, for example.
